(57) **CLAIM**

I claim the ornamental design for a three dimensional motion platform, as shown and described.

DESCRIPTION

FIG. 1 is a top view of my new design for a three dimensional motion platform.

FIG. 2 is a perspective side view thereof.

FIG. 3 is a perspective rear view of the three dimensional motion platform.

FIG. 4 is a perspective front view thereof; and,

FIG. 5 is an isometric view of the three dimensional motion platform.
